DESIGN FOR A NECKTIE RACK

Philip Pestyner, Jamaica, N. Y.

Application April 19, 1945, Serial No. 119,098

Term of patent 14 years

(Cl. D33—8)

To all whom it may concern:

Be it known that I, Philip Pestyner, a citizen of the United States of America and a resident of Jamaica, L. I., in the county of Queens and State of New York, have invented a new, original, and ornamental Design for a Necktie Rack, of which the following is a specification, reference being had to the accompanying drawing, forming part thereof.

In the drawing:

Fig. 1 is a plan view of a necktie rack showing my new design.

Fig. 2 is a side elevation of the same.

I claim:

The ornamental design for a necktie rack, as shown.

PHILIP PESTYNER.
